3,077,018 WIRING CLIP

Clarence W. Cochran, Belmont, Mass., assignor to United-Carr Fastener Corporation, Cambridge, Mass., a corporation of Delaware

Filed July 14, 1959, Ser. No. 826,949

3 Claims. (Cl. 24—73)

This invention relates to clips which are adapted to hold varying sizes and numbers of wires, conduit, tubing and the like, and more specifically, to provide a clip which will prevent the said wires and the like from moving within the clip once it is engaged.

An object of the invention is to provide a clip associated with a strap like liner which will partially circumscribe varying sizes and numbers of wire and the like.

A further object of the invention is to provide a clip which will securely hold varying sizes and numbers of wire, conduit, and the like to a support.

Other objects of the invention will, in part, be obvious, and will, in part, appear hereinafter.

In the drawing:

FIG. 1 is a plan view of the clip;

FIG. 2 is a side elevation of the clip and liner;

FIG. 3 is a plan view of the liner with the center portion broken away;

FIG. 4 is a side elevation of the liner with the center portion broken away;

FIG. 5 is a section of the clip and liner engaged with an apertured support and a single wire; and

FIG. 6 is a section of the clip and liner engaged with an apertured support and a conduit of several wires.

Referring to the drawing, FIGS. 1 through 4, there is shown a clip 10, and a liner 12. The clip 10 has a pair of arms integral with a bight portion 14 to form a generally U-shaped construction. The two arms, referred to as a support engaging arm 16 and a clamping arm 18, according to their function, are in spaced opposed relationship, as best shown in FIG. 2. The clamping arm 18 has a terminal end 20 which is bent first in a direction converging on the arm 16 and then flared away from the said arm 16 to form a substantially V-shaped portion whose portion closest to the arm 16 will be referred to as an apex 22. An aperture 24 is formed in the center of the apex 22. The support engaging arm 16 is dished toward the apex 22 of the clamping arm 18 to form a cupped portion 26 as shown in FIG. 2. An entry aperture 40 is formed in the center of the cupped portion 26 having the substantially same axis as the aperture 24 of the apex 22. It will be noted that the major portion of the support engaging arm 16 is in substantially spaced parallel relationship with a line drawn from the midpoint of the bight portion 14 to a point between the apex 22 and the cupped portion 26 while the major portion of the clamping arm 18 is in spaced angular relationship with said line. The significance of these facts will be pointed out hereinafter. At a predetermined distance from the bight portion 14, a fastener element 28 is formed from the support engaging arm 16. The fastener element 28 may be any configuration necessary to engage a support 30. However, applicant has shown the element 28 as sheared from a portion of the bight 14 and the support engaging arm 16 in the general shape of a letter S. In other words, the element 28 comprises an arched portion with a free end 32, said end 32 is bent to diverge from the support engaging arm 16 and has a convex portion 34 at the point where the said free end is bent. The said element 28 lies below the support engaging arm 16 when the clip 10 is in its normal position and may contact the said support engaging arm 16 at its convex portion 34 as shown in FIG. 2. The liner 12 comprises a flat, strip portion 36 having one

2

terminus tapered 37 and the other terminus formed into an ellipsoid 38 as best shown in FIG. 4. Almost any form may be used rather than the ellipsoid 38, such as a sphere, rectangle, etc. as long as it will fit snugly into the cupped portion 26 in a manner to be described herein-after.

To engage the liner 12 with the clip 10 the tapered terminus 37 of the strip portion 36 is passed between the walls of the entry aperture 40 in the cupped portion 26 and then through the walls of the aperture 24 formed in the apex 22. The liner 12 is then pulled in a direction away from the cupped portion 26 until the ellipsoid 38 rests against the edges adjacent the aperture 40. The width of the aperture 40 is, of course, smaller than the width of the ellipsoid 38 so that the ellipsoid 38 cannot easily be drawn between the walls of the aperture 40. The height of the cupped portion 26 should be slightly less than the thickness of the ellipsoid 38 so that when the liner 12 is fully drawn up, the bottom of the ellipsoid will fall slightly below the line of the major portion of the support engaging arm 16, as shown in FIG. 2. This will prevent the ellipsoid 38 from interfering with an even contact between the support 30 and the support engaging arm 16. The liner 12 may be made of plastic, rubber, leather or other flexible and compressible material. The applicant has used certain formulations of vinyl very successfully. The compressibility feature is necessary so that the thicker ellipsoid 38 can be compressed into the smaller height of the cupped portion 26.

30 To engage the clip 10 and the liner 12 to an apertured support 30, the fastener element 28 is engaged with the walls of the support aperture 42 with the convex portion 34 of the fastener element 28 resting against one side of the support 30 and the support engaging arm 16 resting against the opposite side as shown in FIG. 6. The ellipsoid 38 of the liner 12 is securely held between support 30 and the cupped portion 26 of the support engaging arm 16 as shown in FIGS. 5 and 6.

To engage a wire 44 with the clip 10 and liner 12, the wire 44 is passed between the apex 22 of the terminal end 20 of the clamping arm 18 and the cupped portion 26 of the support engaging arm 16 with the axis of the wire 44 in right angle relationship with the axis of the aperture 24 and the entry aperture 40. As the wire 44 continues past the cupped portion 26, it presses the flat strip portion 36 of the liner 12 toward the bight portion 14 and between the arms 16 and 18. This action also causes the free end of the strip portion 36 lying above the clamping arm 18 to be shortened as the said portion 36 partially circumscribes the wire 44 and substantially follows the contours of a part of the support engaging arm 16 and the clamping arm 18 as shown in FIGS. 5 and 6. Because of the narrow neck formed by the apex 22 and the cupped portion 26, the strip portion 36 therefore forms a circumference greater than 180° which in turn results in a tight holding action of the wire 44 to the clip 10 by the liner 12.

The form of the arms 16 and 18 becomes of greater importance when a wire 44 of comparatively great diameter is engaged with the clip 10 and the liner 12. The angular relationship of the clamping arm 18 with line drawn from the bight portion 14 coupled with its being bent in a converging direction toward the engaging arm 16 has a twofold effect in securely holding the wire 44. 60 In the first place, the construction tends to increase the number of degrees that the liner 12 will circumscribe the wire 44 and secondly, to act as a stop to prevent the wire from being pulled from the clip 10. The terminal end of the support engaging arm 16 may be flared away from the clamping arm 18 to assist in engagement of the wire 44 with the clip 10.

Since certain other obvious modifications may be made

in this device without departing from the scope of the invention, it is intended that all matter contained herein be interpreted in an illustrative and not in a limiting sense.

I claim:

1. A fastening assembly for axial insertion in an apertured work support adapted to retain one or more conduits, or wires and the like to the support including a pair of spaced arms joined by a bight, support engaging means extending downwardly from a medial lateral portion of one of said arms, and a pliable liner passing through an aperture in one of said arms adjacent a free end thereof and passing through an aperture in the other of said arms and defining a closure adjacent to free ends of said arms, said liner adapted for lateral movement between said arms upon insertion of a conduit, wire and the like, and one end of said liner having a bulbous portion of greater cross-sectional area than the aperture in the first of said arms and the other end tapered to facilitate insertion through the aperture of the second of said arms.

2. A fastening clip assembly for holding one or more wires, conduits, and the like, to a work support, said fastener clip assembly including a spring clip member having a pair of spaced arms joined by a bight and having a work support engaging means whereby said fastener clip assembly may be attached to a work support, and a pliable liner, passing through an aperture in one of said arms adjacent a free end thereof and being attached to the other of said arms adjacent a free end thereof and normally defining a closure adjacent free ends of said

5 10 15

arms, a portion of said liner adapted for lateral movement between said arms upon insertion of a wire, conduit, or the like, to protect the wire, conduit, or the like, against contact with the clip when inserted between said arms.

3. A fastening assembly for attachment to a work support to retain one or more conduits, wires, or the like, to the support including a pair of spaced arms joined by a bight, and a pliable liner passing through an aperture in one of said arms adjacent a free end thereof and passing through an aperture in the other of said arms adjacent a free end thereof and defining a closure adjacent free ends of said arms, said liner adapted for lateral movement between said arms upon insertion of a conduit, wire, or the like, and one end of said liner having a portion of greater cross sectional area than the aperture in the first of said arms to prevent disassembly of the liner from said arm when it is being moved laterally between said arms.
